BOOK PAGE MARKER

Wesley M. Cowen, New York, N. Y.

Application December 16, 1950, Serial No. 13,471

Term of patent 14 years

(Cl. D6—1)

To all whom it may concern:

Be it known that I, Wesley M. Cowen, a citizen of the United States and resident of New York, in the county of New York, State of New York, have invented a new, original, and ornamental Design for a Book Page Marker, of which the following is a specification, reference being had to the accompanying drawing, forming a part thereof, and of which

Fig. 1 is a perspective view of a book page marker, showing my new design in full lines, the fragment of a book shown in broken lines is for illustrative purposes only.

Figs. 2 and 3 are top plan and front elevational views respectively, of the book page marker embodying my new design shown in Fig. 1, and

Fig. 4 is an end view of my new design.

I claim:

The ornamental design for a book page marker, as shown and described.

WESLEY M. COWEN.
